INVENTOR,

William James Sidis

UNITED STATES PATENT OFFICE.

WILLIAM JAMES SIDIS, OF NEW YORK, N. Y.

PERPETUAL CALENDAR.

Application filed December 15, 1927. Serial No. 240,214.

The invention relates to perpetual calendars in which week-days can be found directly for any given date whatever; and its object is, first, to provide a means by which 5 all such week-days can be looked up in a direct, simple, and easily understandable manner; secondly, to avoid the cross-reference tables or complex mechanism, one or the other of which have hitherto generally 10 been features of perpetual calendars providing means to look up the week-day of any given date whatever; thirdly, to provide a perpetual calendar in which, once the calendar is adjusted for any given year, a complete 15 and condensed calendar for the year is at once plainly visible.

The accompanying drawing illustrates the invention, a complete front view of the two-slot arrangement being shown in Figure 1; 20 Figure 2 illustrates the back sheet or disk belonging to that form of the invention; while Figure 3 shows a front view of the left half of the indicator form of the invention, the arrangement of the right half being 25 identical with that in Figure 1.

The essential features of the calendar are a top or front sheet (see Fig. 1) and a bottom or back sheet (see Fig. 2), in disk form, so pivoted at its center that it can rotate 30 freely behind the front sheet.

The said back sheet (see Fig. 2) consists of two concentric sections, the month-section (1) and the year-section (2).

The month-section (1) consists of 24, 25, 35 or 26 sectors, each containing the name of a month or a set of such names. The first seven such sectors shall be filled in the following cyclical order: (a) October; (b) May; (c) February, August; (d) March, 40 November; (e) June; (f) September, December; (g) January, April, July. The six following sectors shall be a repetition of the first six sectors, and in the same order. The last seven sectors shall be filled in the following cyclical order: (a) February, March, 45 November; (b) June; (c) September, December; (d) April, July; (e) January, October; (f) May; (g) August; while the six sectors preceding these shall duplicate the last six sectors, and in the same order. This provides a cyclical order for the first thirteen and for the last thirteen sectors, thus 50 making 26 sectors possible; but, as in the illustration, as many as two sectors can be 55 made common to the two classes, thus bring-

ing the total number of sectors down by one or two, to 25 or 24.

The year-section (2) shall consist of a group of leap-years (3) in seven sectors, to correspond with the first seven sectors of 60 the month-section (1); and a group of non-leap-years (4) in seven sectors, to correspond to the first seven of the last thirteen sectors of said month-section. The angle between corresponding sectors in the year- 65 section and the month-section must be in all cases the same, to correspond to the angle on the front sheet between the initial edge of the year-slot (5) and that of the month-slot (6).

All the years within a definite period (in this instance, 1900 to 1956) are placed in one of the fourteen sectors mentioned in the preceding paragraph, each such year being placed in the leap-year sectors or in the non-leap-year sectors according to whether it is or is not a leap-year; and each year being further placed in the sector corresponding to the months beginning in that year with the week-day (Sunday in the present instance) found in the first row and first column of the week-day group (7) on the front sheet.

The front sheet (see Fig. 1) of the calendar has two perforations, a month-slot (6) 85 to slide over the month-section (1) of the back sheet, equal in width to the month-section, and with such length that just seven sectors of the month-section can be seen at once through the month-slot; also a year-slot (5) whose size, shape, and position is such that just one sector of the year-section (2) of the back sheet is visible through it, said sector to be the one corresponding to the first sector visible through the month-slot. 90

Upon the front sheet of the calendar also is a group of week days (7) arranged in seven rows and seven columns so that in each row and in each column the seven 100 days of the week appear in the cyclical order in which they occur, and so that the seven rows shall be continuations of the seven sectors of the month-section to be visible through the month-slot (6); also a group 105 of the numbers from 1 to 31 (8), occupying the continuation of the seven columns of the week-day group (7), the said numbers being listed in succession, row by row.

In addition, the front sheet of the calendar 110

should contain a conversion-table (9) stating how many years have to be added or subtracted in order to use the calendar for years not listed in the year-section (2) of the back sheet.

The year-section may be removed entirely from the back sheet, and the years be arranged in similar fashion (see Fig. 3) in a circle about the pivot (10) as center, on the 10 front sheet of the disk form. If the years are indicated in this manner, an indicator (11) firmly attached to the back sheet, and rotating with it, must be used to replace the year-slot (5).

15. The pivot (10) furnishes a means by which the back sheet, may be so adjusted that the year desired will appear through the year-slot (the conversion-table to be used in the case of years not within the period 20 covered on the back sheet). When this is done, the months appearing through the month-slot, and the week-days and date-numbers on the front sheet, will together constitute a complete and condensed calendar 25 for the year in question; the week-day for any given date being that located in the same row as the month, and in the same

column as the day of the month. In case the indicator form shown in Fig. 3 is used, the calendar is to be so adjusted that the 30 indicator points to the year desired, after which the calendar is to be used in the same manner as above described in this paragraph.

I claim:

The combination, in a perpetual calendar, 35 of a disk containing the months properly grouped in successive sectors; a front sheet with a perforation making seven of those sectors visible when the disk is properly adjusted behind it, and containing years 40 properly grouped in sectors continuous with those or in other sectors of the same circle, as well as week-days grouped in seven rows 45 and seven columns the seven rows co-operating with the seven month sectors, and the numbers 1 to 31 arranged in a continuation of those columns; also a pivot at the center of the disk and fastened to the front sheet at the central point of the year-sectors, with an indicator attached to said pivot and 50 rotating with the disk, which can be made at will to point to any year listed on the front sheet.

WILLIAM JAMES SIDIS.
